[57] CLAIM

The ornamental design for the load binder, as shown and described.

DESCRIPTION

FIG. 1 is an isometric view of the load binder of this invention;

FIG. 2 is a top view thereof;

FIG. 3 is a right side view, the left side view being a mirror image thereof;

FIG. 4 is a bottom view thereof;

FIG. 5 is a front view thereof; and

FIG. 6 is a back view of the invention.

FIG. 1.

FIG. 2.

FIG. 3.

FIG. 4.

FIG. 5.

FIG. 6.
